UNITED STATES PATENT OFFICE.

GEORGE G. GROWER, OF ANSONIA, CONNECTICUT.

REGISTERING APPARATUS.

1,346,100.

Specification of Letters Patent.

Patented July 6, 1920.

Application filed May 31, 1918, Serial No. 237,537.

Renewed August 26, 1919. Serial No. 320,052.

To all whom it may concern:

Be it known that I, GEORGE G. GROWER, a citizen of the United States, residing at Ansonia, in the county of New Haven and State 5 of Connecticut, have invented new and useful Improvements in Registering Apparatus, of which the following is a specification.

The apparatus which is the subject matter of the present application for patent is designed to indicate the number of operations 10 of a machine and the net time consumed by each operation, the apparatus being intended for use in shops employing machines which are operated intermittently but are run constantly. 15

The invention has for its object to provide a registering apparatus of the kind stated which is simple in construction and thoroughly reliable and efficient in operation, 20 and to this end it consists in a novel combination and arrangement of parts to be hereinafter described.

In order that the invention may be better understood, reference is had to the accompanying drawing forming a part of this 25 specification, and in said drawing,

Figure 1 is an elevation of the registering apparatus;

Fig. 2 is a plan view thereof;

Fig. 3 is a side elevation;

Fig. 4 is an elevation showing the parts in Fig. 3 in another position, and

Fig. 5 is a diagram.

Referring specifically to the drawing, 5 and 6 denote two frame plates which are connected in laterally spaced relation by cross bolts 7. This frame supports the registering mechanism and it may be modified in various ways to provide a suitable support 10 for said mechanism.

Between the frame plates 5 and 6, there is pivotally mounted on one of the cross bolts 7, a series of three plates which are arranged side by side. These plates are denoted by 15 the reference characters 8, 9 and 10, respectively, and they are movable independently of each other. Each plate may be pivotally connected to the bolt by being curved around the same at one end, as shown.

Rigidly fastened to one side of the middle plate 9, at its outer end, is an armature 11, the ends of which are directly over the poles of an electro-magnet 12 and also under the free ends of the plates 8 and 10. When the 20 magnet is energized the armature is pulled down, but at other times it is held elevated

by a spring 13 connected to the back of the plate 9 at one end and anchored at its other end to one of the bolts 7.

At 14 and 15 are shown two registering devices or counters of conventional design, these being attached to the plates 8 and 10. The registers operate right and left-handed, respectively, and each is provided with an actuating gear, the gear of the register 14 65 being shown at 16, and that of the register 15 at 17.

The frame plates 5 and 6 also support a transverse shaft 18 which is rotated at a constant rate of speed, say once a second, by 70 some source of power, and on this shaft are two gear wheels 19 and 20 respectively, the former being opposite the gear 16 and the latter opposite the gear 17. Normally these gears are out of mesh for the reason that the 75 spring 13 retracts the plate 9 and the armature 11 extends across the outer ends of the plates 8 and 10 carrying the registers 14 and 15. When the magnet 12 is energized, the armature 11 is pulled down releasing the 80 plates 8 and 10 so that they drop down of their own weight, and as they carry the registers 14 and 15, with their actuating gears 16 and 17, said gears come in mesh with the 85 gears 19 and 20.

The gear 16 is complete and will therefore keep turning to actuate the register 14 as long as the magnet 12 is energized, and consequently the register will register the number of revolutions made by the shaft 18; or 90 in other words it indicates time.

The gear 17 is mutilated, some of its teeth being removed, so that after making a partial revolution, it comes out of mesh with the gear 20, and a spring 21 connected to 95 the former would turn it the rest of the way, were it not for a stop 22 attached to the plate 6. This stop engages a pin 23 standing out from one side of the gear 17 and prevents this further motion of the gear as 100 long as the magnet 12 is energized. When the magnet is deenergized, the spring 13 retracts the plates 8, 9 and 10 and the registers 14 and 15, with their gears 16 and 17, whereupon the pin 23 slips off the stop 22, 105 and the spring 21 now pulls the gear 17 around through the remaining part of one revolution, and leaves it in proper position for the next operation. It will therefore be seen that the register 15 will register one 110 for each time the magnet 12 is energized.

At 24 is shown an electric motor driving

- a machine shown diagrammatically at 25. In the line wire 26 of this motor is interposed a circuit breaker 27 which may be a solenoid relay or similar device, the same 5 controlling a branch circuit 28 leading from a local circuit 29 which furnishes current to the magnet 12. The current source of this local circuit is shown at 30, and in said circuit is interposed a resistance 31.
- 10 The main circuit 26 of the motor 24 is through the relay 27 but it has not sufficient current to operate the relay when the machine 25 is running free. When a load is thrown on the machine, the increased current 15 in the line energizes the relay and breaks the relay circuit. When the machine is running free and the branch circuit 28 is closed, the current from the source 30 passes through the resistance 31 and the relay, and 20 back to the source, by the way of the branch circuit 28, the registering apparatus being now short-circuited so that no current goes to the magnets 12. When the machine 25 is loaded, the increased current in the motor 25 circuit draws the solenoid coil and opens the branch circuit 28, and the current from the source 30 now goes to the magnets 12 to operate the registers 14 and 15 hereinbefore described. To connect the registers to 30 any other machine any device which opens the circuit when the load is thrown on may be used instead of the solenoid relay 27, the action being then similar to that just described.
- 35 It will be evident that the shaft 18 may operate any number of registering units according to the number of machines in the establishment.

I claim:

- 40 1. The combination of an electric motor and its energizing circuit, a time registering device, a register recording the number of actuations of said time register, electro-responsive means controlling said registers, 45 and electro-responsive means interposed in the motor energizing circuit and controlling the first mentioned electro-responsive means.
2. The combination of an electric motor and its energizing circuit, a machine driven 50 by the motor, a time registering device, a register recording the number of actuations of said time register, electro-responsive means controlling said registers, and electro-responsive means interposed in the motor 55 energizing circuit and controlling the first mentioned electro-responsive means, said second-mentioned electro-responsive means responding to fluctuations in the current of the motor energizing circuit produced by 60 loading the machine driven by the motor.
3. The combination of an electric motor and its energizing circuit, a machine driven by the motor, a time registering device, a register recording the number of actuations 65 of said time register, electro-responsive

means controlling said registers, and electro-responsive means interposed in the motor energizing circuit and controlling the first mentioned electro-responsive means, said second-mentioned electro-responsive means 70 responding to fluctuations in the current of the motor energizing circuit.

4. The combination of an electric motor and its energizing circuit, a machine driven by the motor, a time registering device, a register recording the number of actuations of said time register, electro-responsive means controlling said registers, a local circuit energizing said means, a branch leading from said circuit, a relay interposed in 80 the motor energizing circuit and controlling the branch circuit, said branch circuit when closed short-circuiting the electro-responsive means which control the aforesaid registers. 85

5. The combination of an electric motor and its energizing circuit, a machine driven by the motor, a time registering device, a register recording the number of actuations of said time register, electro-responsive 90 means controlling said registers, a local circuit energizing said means, a branch leading from said circuit, a relay interposed in the motor energizing circuit and controlling the branch circuit, said branch circuit when 95 closed short-circuiting the electro-responsive means which control the aforesaid registers, and the relay responding to fluctuations in the current of the motor energizing circuit produced by loading the machine driven by the motor. 100

6. The combination of an electric motor and its energizing circuit, a machine driven by the motor, a time registering device, a register recording the number of actuations 105 of said time register, electro-responsive means controlling said registers, a local circuit energizing said means, a branch leading from said circuit, a relay interposed in the motor energizing circuit and controlling the 110 branch circuit, said branch circuit when closed short-circuiting the electro-responsive means which control the aforesaid registers, and the relay responding to fluctuations in the current of the motor energizing circuit. 115

7. The combination of an electric motor and its energizing circuit, a machine driven by the motor, a time registering device, a register recording the number of actuations of said time register, electro-responsive 120 means controlling said registers, and controlling means for said electro-responsive means responding to fluctuations in the current of the motor energizing circuit produced by loading the machine driven by the 125 motor.

8. The combination of an electric motor and its energizing circuit, a machine driven by the motor, a time registering device, a register recording the number of actuations 130

of said time register, electro-responsive means controlling said registers, and controlling means for said electro-responsive means responding to fluctuations in the current of the motor energizing circuit.

9. The combination of an electric motor and its energizing circuit, a time registering device, a register recording the number of actuations of said time register, electro-responsive means controlling said registers, and controlling means for said electro-responsive means responding to fluctuations in the current of the motor energizing circuit.

10. The combination of an electric motor and its energizing circuit, a time registering device, a register recording the number of actuations of said time register, electro-responsive means controlling said registers, a local circuit energizing said means, a branch leading from said circuit, a relay interposed in the motor energizing circuit and controlling the branch circuit, said branch circuit when closed short-circuiting the electro-responsive means which control the aforesaid registers.

11. The combination of an electric motor and its energizing circuit, a time registering device, a register recording the number of actuations of said time register, electro-responsive means controlling said registers, a local circuit energizing said means, a branch leading from said circuit, a relay interposed in the motor energizing circuit and controlling the branch circuit, said branch circuit when closed short-circuiting the electro-responsive means which control the aforesaid registers.

sponsive means which control the aforesaid registers, the relay responding to fluctuations in the current of the motor energizing circuit.

12. In an apparatus of the kind stated, an intermittently operated time registering device, electro-responsive means for controlling the operation of said register, and a register recording the number of actuations of the time register.

13. In an apparatus of the kind stated, an intermittently operated time registering device, electro-responsive means for controlling the operation of said register, and a register recording the number of times said electro-responsive device operates.

14. In an apparatus of the kind stated, an intermittently operated time registering device having an actuating gear, a register for recording the number of actuations of said registering device, and having a mutilated actuating gear, a swinging support for each register, an electro-magnet for swinging the supports in one direction, means for swinging the supports in another direction when the magnet is deenergized, a drive shaft, drive gears on said shaft opposite the aforesaid actuating gears and adapted to mesh therewith when the supports swing in one direction, and means for turning the mutilated gear a distance to complete one revolution when its blank portion reaches its drive gear.

In testimony whereof I affix my signature.
GEORGE G. GROWER.
